US00D846107S

(12) **United States Design Patent** (10) **Patent No.:** **US D846,107 S**
(45) **Date of Patent:** **** Apr. 16, 2019**

(54) **AROMA DIFFUSER**

(71) Applicant: **Shenzhen DiTuo Electronic Co.,Ltd.**,
Shenzhen (CN)

(72) Inventor: **Yangmin Hu**, Guangzhou (CN)

(73) Assignee: **Shenzhen DiTuo Electronic Co., Ltd.**,
Shenzhen (CN)

(**) Term: **15 Years**

(21) Appl. No.: **29/617,226**

(22) Filed: **Sep. 12, 2017**

(51) LOC (11) Cl. **28-99**

(52) U.S. Cl.

USPC **D23/366**

(58) **Field of Classification Search**

USPC D23/314, 325, 333-336, 355-367,

D23/386-388; D11/143-154

CPC . A61L 9/03; A61L 9/012; A61L 9/015; A61L

9/037

(57) **CLAIM**

The ornamental design for an aroma diffuser, as shown and described.

DESCRIPTION

FIG. 1 is a perspective view of an aroma diffuser showing my new design;

FIG. 2 is a front view thereof;

FIG. 3 is a rear view thereof;

FIG. 4 is a left view thereof;

FIG. 5 is a right view thereof;

FIG. 6 is a top side view thereof; and,

FIG. 7 is a bottom side view thereof.

The broken lines depict portions of an aroma diffuser in which the design is embodied that form no part of the claimed design.
